METHOD AND CIRCUIT FOR REDUCING THE
EFFECT OF NOISE PULSESMadison G. Nicholson, Verona, N. J., assignor to
National Union Radio Corporation, Newark,
N. J., a corporation of New Jersey

Application April 13, 1940, Serial No. 329,407

3 Claims. (Cl. 250—20)

My invention relates to a new and improved method and to a new and improved circuit for reducing the effect of noise pulses, such as static, interference resulting from the operation of X-ray machines and other electrical apparatus, in the circuits of radio receiving sets.

One of the objects of my invention is to reduce or eliminate the effect of noise pulses, anterior to the detector of the set.

Another object of the invention is to by-pass the noise pulse anterior to the detector, either wholly or partially, by means of a suitable limiting device, as a diode or other rectifier, while maintaining said limiting device under a bias or counter-voltage which will prevent the by-passing of any portion of the carrier wave, if it is unmodulated or under normal audio modulation for voice, music, etc.

Another object of the invention is to secure said bias by means of a suitable rectifier, such as a diode.

Another object of the invention is to provide a predetermined interval of time before the effect of a noise pulse on the bias voltage device is transmitted to the limiting device.

Another object of the invention is to provide a simple circuit, which will operate by means of a pair of rectifiers, such as diodes, combined with suitable impedances, which are preferably resistances which have minimum induction.

Other objects of the invention will be stated in the following description and drawing which set forth preferred embodiments of the invention, it being understood that the above general statement of the objects of the invention is intended generally to explain the same, without limiting it in any manner.

Fig. 1 is a circuit diagram of one embodiment of the invention.

Fig. 2 is a circuit diagram of a second embodiment.

Fig. 3 is a circuit diagram of a third embodiment.

In order fully to describe the invention, preferred examples thereof are stated, giving certain values of capacities, inductances, etc. However, the invention is not limited to said preferred examples, or to any part thereof.

In Fig. 1, the member 1 is an electronic tube, which may be the last intermediate frequency amplifier of a superheterodyne receiving set. The invention is not limited to any particular type of set or circuit or device for receiving or detecting electric waves, save that the improved limiting means are preferably, but not necessarily,

used anterior the audio amplifying stage or stages.

The cathode of tube 1 is grounded at 1c. The anode of tube 1 is connected to one end of the 5 primary coil P of a step-down transformer 2. The other end of coil P is connected at 1d to the positive terminal of a suitable source of direct current. The other end of said source is grounded. The anode supply and cathode of 10 tube 1 are also connected by a condenser 1a whose capacity is 0.1 microfarad.

The step-down transformer 2 has an effective ratio of primary voltage to secondary voltage of one to 0.45 when the secondary coil S is loaded 15 by the audio output diode 3. This diode 3 has a resistance load which is supplied by potentiometer 4. This has a resistance of 0.5 megohm. Said potentiometer 4 is also used as the volume control for the audio output 5. The potentiometer 4 is by-passed at said intermediate frequency by condenser 6, whose capacity is 50 micro-microfarads.

The primary coil P has an inductance of 2 millihenries. Said coil P is tuned to resonate 25 at said intermediate frequency by a variable trimmer condenser 7, whose capacity can be varied from 20 to 60 micro-microfarads. Said intermediate frequency is 455 kilocycles.

The secondary coil S has an inductance of 1 30 millihenry. It is tuned to resonate at said intermediate frequency of 455 kilocycles by a variable trimmer condenser 8, whose capacity can be varied from 70 to 140 micro-microfarads.

The primary and secondary coils P and S are 35 mutually coupled so that the effective step-down ratio of the transformer is as previously stated (1 to 0.45) and this value of coupling is approximately 70% of the value for critical coupling.

40. The anode of tube 1 is connected at 1b to the terminal 10a of condenser 10, whose capacity is 100 micro-microfarads. The other terminal 10b of condenser 10 is connected to the ground at 9a through the bias-voltage diode 9. Terminal 45 10b is connected to the anode of diode 9. Said diode 9 and the other diode 14 are identical. These diodes 9 and 14 are designated in the trade as "R. M. A. Type 6H4GT." Each said diode has a dynamic resistance of about one thousand ohms, under the operating conditions utilized herein, at 0.25 milliampere anode current.

45. The anode of diode 9 and the terminal 10b of condenser 10 are connected to the ground at 9a through resistance 11, of 1 megohm. Terminal 10b of condenser 10 and said anode are 50

also connected through resistance 12 of 2 megohms, to the terminal 13a of condenser 13, and to the anode of diode 14. Said condenser 13 has 0.1 microfarad capacity. The terminal 13b of condenser 13 is grounded at 13c.

The limiting diode 14 has its cathode connected to the line and to the cathode of detector diode 3, anterior the first audio stage.

The improved method and the operation of the improved circuit are as follows:

Assume that an unmodulated signal or carrier wave is applied to the primary coil P and that this unmodulated carrier wave has a peak voltage of 10 volts. The effect is the same as though the terminal 10a of the condenser 10 were connected to one terminal of an alternator, the other terminal of said alternator being grounded. This alternator would impress an alternating voltage upon the terminal 10a. While the applied alternating voltage varies in value from minus 10 volts to plus 10 volts, current will flow through the condenser 10, in the direction of the arrow A. This may be designated as the charging current of the condenser 10. Substantially all of this charging current will pass directly to the ground at 9a through the diode 9, since the internal resistance of the diode 9 is relatively low, compared to the values of the resistances 11 and 12. Part of this charging current will be by-passed through the resistance 11 to the ground at 9a. Part of this charging current will pass through the resistance 12 to the point 12a. From the point 12a part of the charging current will flow through the diode 14 to the ground at 8a, and part thereof will flow through the condenser 13 to the ground at 13c, thus impressing a charge upon the condenser 13 so that the terminal 13a thereof will be at a higher voltage than the terminal 13b thereof. The voltage and charge which are thus impressed upon the condenser 13 will be very small.

During the next half-cycle, when the voltage which is impressed upon the condenser 10 drops from plus 10 volts to minus 10 volts, the current will flow through the condenser 10 in the direction of the arrow B instead of in the direction of the arrow A. This may be designated as the discharging period of the condenser 10. During this discharging period no current flows from the ground at 9a through the diode 9 to the terminal 10b. Current will flow from the ground at 9a through the resistance 11 to the terminal 10b and through condenser 10 to the ground. Current will also flow from the ground at 13c through the condenser 13 to the point 12a, and through the resistance 12 to the terminal 10b. This discharge circuit of the condenser 13 omits the resistance 11. At the end of the first complete cycle of the impressed voltage of the unmodulated signal or carrier wave, a negative charge will have been impressed upon the condenser 13, so that the terminal 13b thereof will have a higher voltage than the terminal 13a. This effect is cumulative so that the required biasing charge will be impressed upon the condenser 13 and upon the anode of the diode 14 in a negligible period of time. Hence no current can pass through diode 14 until the negative voltage which is impressed upon its cathode will exceed the negative bias voltage which is thus impressed upon its anode. The value of the negative voltages which is thus impressed upon the condenser 13 and upon the anode of the diode 14, depends upon the value of the resistance 11. For example, if the value of the resistance

11 is relatively small, a larger percentage of the current which flows through the condenser 10 during the discharge period thereof, will flow directly from the ground at 9a through the resistance 11 to the terminal 10b. Since the value of resistor 11 is very large, compared to the dynamic resistance of the associated diode 9, the current through condenser 10 during the discharge period is small. The capacity of the condenser 13 is made sufficiently large so that its negative voltage will be substantially constant, thus eliminating the effect of the variation in the impressed voltage of the unmodulated signal wave or carrier wave. In the specific example 15 which is mentioned herein, a substantially constant negative voltage of nine (9) volts will be impressed upon the anode of the diode 14.

The coils P and S are oppositely wound, but they may be wound in the same direction. The 20 voltage across condenser 13 is substantially constant, as far as the frequencies which pass through transformer 2 are concerned. The variation at this frequency is less than 20 microvolts.

25 If the peak signal voltage of the unmodulated carrier wave across the primary coil P is 10 volts, the peak signal voltage of the unmodulated carrier wave which is applied to the cathode of diode 14 is 4.5 volts. Hence, the maximum negative voltage which can be applied to the cathode of diode 14 by the unmodulated carrier wave is 4.5 volts. Under such conditions, no current will pass through diode 14, because a substantially constant negative counter-voltage of 9 volts is 35 impressed upon the anode of diode 14.

The resistor 12 and condenser 13 act as a filter or smoothing means to smooth the normal audio modulation of the carrier wave, as well as the variations in the unmodulated carrier wave, 40 so that the negative voltage which is impressed upon the anode of diode 14 remains substantially 9 volts, under normal audio modulation, and also when the carrier wave is unmodulated.

When the carrier wave carries audio modulation 45 (voice, music, etc.) the maximum value of the signal voltage is normally twice that of the unmodulated carrier wave. No current will flow through diode 14 under normal modulation, because the maximum negative voltage which is 50 then impressed upon the cathode of diode 14 is 9 volts. The diode 14 is then at the critical stage, and current will flow through said diode if a greater negative voltage is impressed on its cathode.

55 If a noise pulse, such as static or the like, is impressed upon the carrier wave in addition to normal audio modulation, the maximum negative voltage which is impressed upon the cathode of diode 14 will exceed 9 volts. Current will then 60 pass through diode 14, thus diminishing and limiting the amplitude of the noise pulse which is applied to the audio output diode 3. The effect is to by-pass the noise pulse from said diode 3. The noise to signal ratio is thus materially reduced.

65 Since the noise (static) pulse is also applied to the bias voltage diode 9 there is an increase in voltage across diode load resistor 11 during the noise (static) pulse, but there is a time delay before this voltage causes an appreciable change 70 in the voltage across the filter condenser 13, which is impressed upon the diode 14. This is brought about by the combined action of filter resistor 12 and filter condenser 13. If this time delay is greater than the time duration of the noise 75 pulse, the limiting of the noise pulse is already

accomplished before the voltage across filter condenser 13 has been changed from its normal value. This circuit is designed for reduction of noise pulses of durations up to 0.05 second. Most noise (static) pulses are much shorter than this, although several pulses may be grouped together within such a time duration. In this case, however, the total change in bias voltage across condenser 13 and diode 14 is small, because the average voltage during a series of noise pulses is much less than the noise peaks. Hence even with a series of noise pulses, reduction is brought about, provided there is some interval between the noise pulses which permits the signal to get through.

The invention includes by-passing some or all of the noise pulse in any manner, or neutralizing its effect, either wholly or partially, in any manner, anterior the detector. The ground connections shown may be replaced by any other type of connection.

The counter-voltage which is applied to diode 14 is not necessarily constant, although this is preferred.

In the preferred embodiment, the carrier wave is utilized to impress a biasing counter-voltage upon the diode 14. The invention is not limited to this, as said biasing counter-voltage can be secured from any suitable source. If a source of said biasing counter-voltage which is independent of the carrier wave is utilized, it is not necessary to have the diode 9.

Since the cathodes of diodes 3 and 14 are connected to each other, the current passes from the ground at 4a, through the detector diode 3, and through diode 14, only when the limiting conditions stated herein are fulfilled.

This may be designated for the purpose of the claims, by stating that the noise limiting means and the detector are in phase. However, the diode detector 3 may be changed in phase, by reversing its cathode and anode connections, without affecting the noise limiting action.

The detector may be of any type, and the invention is not limited to a detector diode.

The invention is not limited to a circuit which has inductive coupling. Therefore, when I use the designations primary circuit and secondary circuit in the claims, these terms include any type of coupling between the electronic tube 1 and the detector 3.

The resistance and inductance and capacity of the circuit can be disregarded, save as specifically stated herein, and save for the resistances and other values of the tubes of the radio receiving set.

The diodes 9 and 14 can be replaced by any suitable rectifying means.

The condenser 13 may be replaced by any suitable source of direct and substantially constant current which can deliver an adjustable voltage, and whose negative terminal is connected to the anode of diode 14. This will make it possible to eliminate condenser 10, diode 9, and resistances 11 and 12. In the example given, the negative bias of said source of direct current is regulated so that a constant countervoltage of 9 volts is impressed on diode 14, thus preventing it from drawing current, unless the negative voltage which is impressed upon the cathode of diode 14 exceeds minus 9 volts. This is by no means as desirable as the preferred embodiment, but it is within the scope of the invention.

Fig. 2 shows an embodiment in which the transformer 2 is a step-up transformer. The con-

denser 14a of Fig. 2 has the same function and the same capacity as the condenser 13 of Fig. 1. The condenser 15 has the same function as the condenser 10 of Fig. 1, and the potentiometer 4a of Fig. 2 has the same value as the potentiometer 4 of Fig. 1. The transformer 2 of Fig. 2 may be a step-up transformer of 0.45 to 1. The value of the resistance 12a of Fig. 2 is equal to that of the resistance 12 of Fig. 1. One end of the resistance 12a is connected to the anode of the detector diode 3a. In the embodiment of Fig. 2, the diode 3a operates as a detector and it also fulfills the function of diode 9 of Fig. 1. The diode 9a now acts to damp the noise pulses. The condenser 14 impresses the necessary counter-voltage upon the diode 9a, so that said diode will not draw current until the limiting conditions above mentioned have been fulfilled. A separate explanation of the action of the circuit of Fig. 2 is therefore not required. Since the transformers of the embodiments of Figs. 1 and 2 are respectively step-down and step-up transformers, the invention is not necessarily limited to any relation between the voltages at the coils of said transformers.

Fig. 3 shows an embodiment which utilizes added selectivity. The use of the improved noise-reducing system, with the addition of selectivity between the point where the noise is to be limited and the audio detector, will result in an additional reduction of the noise pulse or pulses. The principle is therefore entirely different from that of the well-known method of reducing noise by the use of high selectivity, but without the use of a noise limiting device.

According to my invention the tuning system which is located anterior the noise limiter, passes a frequency band which is wider than the frequency band of the desired signal. The circuit of the radio receiver which is located after the noise limiter, passes a band width which is only equal, or only approximately equal to the band width of the desired signal. This produces a better ratio of signal to noise.

This improvement results from two factors. First, the noise pulses have a wide frequency distribution, which is at least as wide as the band width of the circuit or circuits which precede the noise limiter. Secondly, the noise limiter acts to limit the radio frequency voltage, regardless of frequency distribution.

If the noise pulse has a frequency distribution through a given band width, the action of the noise limiter is to limit the voltage of the noise pulse without materially changing the frequency distribution. However, additional frequencies are generated which fall outside of the frequency band anterior the noise limiter. For example, by using a circuit or circuits whose band width is identical with the band width anterior the noise limiter, between the noise limiter and the audio detector, these additional frequencies which are generated in the limiting process are eliminated. However, if the band width of the circuit or circuits which are intermediate the noise limiter and the audio detector is narrower than the band width of the circuit or circuits which precede the noise limiter, and if said intermediate band width is sufficiently wide to pass all of the desired signal frequencies, only a part of the noise which passes the limiting device will be passed on to the audio detector. Nevertheless, all the desired signal frequencies will be passed on to the detector.

Fig. 3 is substantially identical with Fig. 1 save

that I utilize an additional transformer 16 and a coupling condenser 19. The primary coil of the transformer 16 has the usual condenser 17, and the secondary coil of the transformer 16 has the usual condenser 18. The same parts in Figs. 1 and 3 are designated by the same reference numerals.

The frequency band width which is passed by all the circuit elements in the radio receiver up to and through the transformer 2, must be substantially wider than the frequency band width of the signal, including all the necessary side bands of the signal which result from modulation at the transmitter. The selectivity of the added transformer 16 has a narrower frequency pass characteristic than the anterior circuit elements. The frequency which is passed by the transformer 16 is equal or approximately equal to the signal band-width, including the side bands. The coupling condenser 19 has a small capacity of from 1 to 2 micro-microfarads, depending upon the characteristics of transformer 16. The transformer 2 of Fig. 3 is a stepdown transformer, like the transformer 2 of Fig. 1. The primary and secondary coils of the transformer 16 respectively have the same number of windings so that the transformer 16 merely transmits the signal wave, without changing the peak voltage thereof. The respective inductances of the coils of the transformer 16 depend upon the complete design of the radio receiver, anterior the coupling condenser 19. However, sufficient working data can be given which will be sufficient for one skilled in the art.

It may be assumed that the receiver is a superheterodyne of ultra-high frequency, in the order of 40 megacycles, with an intermediate frequency of 2 megacycles. The band width anterior the coupling condenser 19 may be 200 kilocycles, and the band width of the transformer 16 is only 20 kilocycles. Since the specific example which has been given in connection with Fig. 1 refers to an intermediate frequency of 455 kilocycles, the values of the transformer 2 must be changed in the embodiment of Fig. 3. The noise which passes by the noise limiting device of Fig. 3 will therefore be distributed over 200 kilocycles. The additional selectivity after the noise limiting device, is only 20 kilocycles. Therefore the embodiment of Fig. 3 further reduces the noise pulse or energy to 10% of the value thereof which passes the noise limiting device. Nevertheless, the desired signal passes through the circuit in its entirety, if it covers only 20 kilocycles, which is normal.

The invention which is illustrated in Fig. 3 is not necessarily limited to a step-down transformer 2, or to a transformer 16 of the type shown in said figure. According to my invention,

current is by-passed out of the circuit, anterior the detector stage of the circuit. The detector stage is operated independently of said by-passed current. Likewise, the by-pass circuit is independent of the detector, in the sense that the rectifying action of the detector is not controlled by the by-pass circuit. My circuit is, therefore, wholly different from circuits of the type shown in U. S. Patent No. 2,194,499 in which the currents which resulted from objectionable noise pulses are maintained in the circuit, and said currents are caused to affect the operation of the detector, by impressing a potential bias upon the grid thereof.

I have shown several preferred embodiments of my invention, but it is clear that numerous changes and omissions can be made in said embodiments without departing from the spirit of the invention.

I claim:

1. A radio-receiving circuit which has a plurality of stages, said circuit having one electrode of a by-pass diode connected to said circuit at a point of connection which is subsequent to the first stage which is anterior the detector stage of said circuit, the current in the circuit at said point of connection being the modulated signal current of said circuit, a biasing capacity having a first terminal thereof connected to the anode of said by-pass diode and having the second terminal thereof connected to the ground, a resistance connected in shunt with said biasing capacity between the anode of the by-pass diode and the ground, the first terminal of the biasing capacity being connected to the anode of a supplemental diode whose cathode is grounded, the anode of the supplemental diode being connected to the circuit at a point of said circuit in which the modulated signal current of said circuit flows.

2. A method of diminishing the effect of a noise pulse in a radio-receiving circuit which has a detector stage to which the modulated signal current of said circuit is supplied, which consists in by-passing modulated signal current wholly out of said circuit and anterior said detector stage, said modulated signal current being thus by-passed in a single direction and wholly against a substantially constant countervoltage, producing and maintaining said countervoltage by the unmodulated signal current of said circuit at a value which is substantially equal to the maximum voltage of the signal current under normal audio modulation.

3. A method according to claim 2, in which any substantial change in said countervoltage under the effect of a noise pulse, is delayed up to substantially 0.05 second.

MADISON G. NICHOLSON.
